UNITED STATES PATENT OFFICE.

CHARLES H. APPS, OF EAST ORANGE, NEW JERSEY.

WATER GAUGE.

Application filed October 1, 1921. Serial No. 504,651.

To all whom it may concern:

Be it known that I, CHARLES H. APPS, of East Orange, in the county of Essex and State of New Jersey, have invented a certain new and useful Improvement in Water Gauges, of which improvement the following is a specification.

My invention relates to water gauges for steam boilers, of what is known as the "reflex" type, and its object is to present a gauge of such type which shall be of simple and compact construction, embody a minimum number of parts, occupy small space on the boiler, and be adapted for the reception of one or more reflex glasses, to make possible observation of water level in the boiler from different angles.

The improvement claimed is hereinafter fully set forth.

In the accompanying drawing: Figure 1 is a side view, partly in elevation and partly in section, of a water gauge embodying my invention; Fig. 2, a side view, in elevation, of the body of the gauge; Fig. 3, a plan or top view; Fig. 4, a bottom view; Fig. 5, a transverse section through a double glass gauge; Fig. 6, a similar section through a single glass gauge; Fig. 7, a vertical section through the upper portion of the gauge, showing a detachable stem; and, Fig. 8, a similar section through the lower portion of the body, without a connected stem.

In the practice of my invention, I provide a body, 1, which is of strong metal, as bronze, and is of polygonal (in this instance quadrangular) transverse section, and tapered, or of continuously increasing transverse section, from its upper to its lower end. The body, 1, is fitted in a correspondingly tapered metal case, 2, and is provided, at top, with a tubular stem, 1^a, which, as shown in Figs. 1 and 2, is formed integral with it, and, in Fig. 7, is separate and detachably connected to it. The body and case are drawn, and firmly held together, by a nut, 3, engaging the stem, 1^a, of the body, and bearing, through a washer, 3^a, on the top of the case.

A longitudinal slot, 1^b, is formed in one or more of the sides of the body, 1, and a similar slot, 2^b, (one or more) is formed in the case, 2, the slots of the body and the case being parallel and in line vertically one with the other. Lips, 2^c, are formed on

the opposite sides of each of the slots, 2^b, of the casing, said lips forming shoulders against which, and between them and the sides of the adjoining slot, 1^b, in the body, a strong plate of glass, 4, is fitted. Gaskets, 5, are interposed between the glass, and the surfaces of the casing, and of the body, on which it abuts, and when the body is drawn upwardly in the case, by tightening the nut, 3, a steam and water tight joint is formed between the glass and the enclosing case, by the wedging action exerted upon the glass, in two convergent directions, by the body.

As shown in Figs. 1 and 2, a tubular stem, 1^c, which communicates with the interior of the body, is formed on the bottom thereof, said stem being adapted for connection to a pipe leading to the water space of the boiler, and controlled by a cock or valve. 70 The upper tubular stem, 1^a, is similarly adapted for connection to a pipe leading to the steam space of the boiler and controlled by a cock or valve, and the interior of the body, 1, being thus in communication with 75 the steam and water spaces, respectively, of the boiler, the level of water therein will correspond with that of the water in the boiler and will rise and fall correspondingly therewith. As shown in Fig. 8, the body is 80 not provided with a lower stem, the pipe communicating with the boiler being, in this case, connected directly to the body.

As most clearly shown in Fig. 5, in the water gauge above described, two glasses, 4, 90 are applied, but a greater or less number may be adopted in the discretion of the constructor, without departure from the spirit of my invention. Thus, as shown in Fig. 6, the body may have only a single 95 slot, between which slot and the slot of the case, a single glass, 4, is interposed and tight joints formed between it and the body and case, in the same manner as in the construction first described.

The leading and characteristic structural and operative feature of my invention, and that by which it is differentiated from designs, prior in the art, so far as my knowledge and information extend, consists in the 105 means, substantially as hereinbefore described, whereby wedging action, which effects the sealing of the joints between the case and the glass, or glasses, fitted therein, is exerted, in two convergent directions, by 110

the direct action of a body, which is longitudinally tapered on more than one of its sides, upon a case within which it is fitted, and which is correspondingly tapered.

5 I claim as my invention and desire to secure by Letters Patent:

1. In a water gauge, the combination of a body, which is longitudinally tapered on more than one of its sides; a correspondingly tapered case surrounding said body, one or more glasses interposed between the body and case, and means for effecting a steam tight joint between said glasses and the case, by the exertion of wedging action, 10 in two convergent directions, on the glass or glasses.

2. In a water gauge, the combination of a body, which is longitudinally tapered on more than one of its sides, a correspondingly tapered case surrounding said body, one or more glasses interposed between the body and case, and means for drawing the case to a tight bearing on the glass or glasses.

3. In a water gauge, the combination of a body, which is longitudinally tapered on more than one of its sides, a correspondingly tapered case surrounding said body, one or more glasses interposed between the body

and case, and a nut bearing on the case and engaging a screw on the body.

4. In a water gauge, the combination of a body, which is longitudinally tapered on more than one of its sides; a correspondingly tapered case surrounding said body, one or more glasses interposed between the body and the case, gaskets fitted between the glasses and the case, and means for tightening the case on said gaskets, by the exertion of wedging action, in two convergent directions, on the glass or glasses.

5. In a water gauge, the combination of a body, which is longitudinally tapered on more than one of its sides; tubular stems connected to opposite ends thereof, a correspondingly tapered case, on which the body bears directly throughout; one or more glasses interposed between the body and case, and means for effecting a steam tight joint between said glasses and the case, by the exertion of wedging action, in two convergent directions, on the glass or glasses.

CHARLES H. APPS.
